UNITED STATES PATENT OFFICE.

THEODORE HORTON, OF BLUFFTON, INDIANA, ASSIGNOR TO HIMSELF, AND WASHINGTON I. FITCH AND WILLIAM W. WISILL, SR., BOTH OF SAME PLACE.

HAND CORN-PLANTER.

SPECIFICATION forming part of Letters Patent No. 257,820, dated May 9, 1882.

Application filed February 18, 1882. (No model.)

To all whom it may concern:

Be it known that I, THEODORE HORTON, of Bluffton, in the county of Wells and State of Indiana, have invented certain new and useful Improvements in Hand Corn-Planters; and I do hereby declare that the following is a full, clear, and exact description thereof, reference being had to the accompanying drawings, and to the letters of reference marked thereon, which form part of this specification.

This invention relates to improvements on hand corn-planters; and the nature of my invention consists in the combination, with a flat staff having a double grasping-handle, a spring-discharger, and a hopper, of a novel means, hereinafter explained, whereby the operator with one hand can handle the implement and effect the discharge of the corn in regular graduated quantities.

My invention has reference especially to the construction of the cast-metal frame or bracket on which the bottom of the hopper is fitted, and to which the cut-off is directly applied; also, to means for giving an intermittent rotary movement to the dropping-wheel, and actuating the cut-off, which is located beneath this wheel, as will be hereinafter described.

The following description of my invention, when taken in connection with the annexed drawings, will enable others skilled in the art to fully understand it.

Figure 1 is a side elevation. Fig. 2 is a central vertical section through the bottom of the seed-box. Fig. 3 is a perspective view of the casting of the bottom of the seed-box. Fig. 4 is a plan view of the same.

A designates the flat staff of the implement; B, the hopper for containing the corn to be dropped in suitable charges; C, a flat point or penetrating plate, which is straight with the staff; and D, a slightly-bent point or thrusting plate, which is made of spring metal, and which is so shaped and applied to the staff that its lower end closes by its own spring action against the lower end of the rigidly-fixed plate or point C. A short arm, *a*, is secured rigidly to the spring-plate D, and this arm is connected by a rod or link, *b*, to a curved lever, E, which is pivoted to a bracket, E', fixed to the back of the staff A. The outer or shortest arm of lever E is connected by a rod, *c*, to a

finger-lever, F, which is pivoted to the back of the staff in such close relation to a T-handle, A', that the operator, while grasping this handle by one hand, can operate the said lever by 55 the same hand and spring the plate D from the plate or point C when he desires to drop a charge of corn into the hole made by thrusting said plates into the soil.

G designates a cast-metal frame or bracket, 6c which is rigidly secured to the edges of the staff by means of screws passed through ears *d*, cast on this plate or frame. Lugs *e* are cast on the upper side of the frame G, as shown in Fig. 3, so as to receive the lower edges of 65 the hopper B and to sustain the same both inside and outside and afford stiffness thereto. That edge of the frame G which abuts against the face of the staff A is also constructed with lugs *f*, which depend from it and afford a firm 70 bearing for the same. The frame G has a large opening through it, on one side of which is a raised gateway, *g*, having a rectangular entrance, which is closed by means of a flexible gate or cut-off, *g'*, preferably made of a loop of 75 flat india-rubber secured by a rivet to the vertical lip of the gateway. The bottom of the frame G is flat, and has fitted closely to it the flat top of the perforated dropping-wheel H. This wheel rests upon the flat top of a bracket, 80 J, which is rigidly secured to the face of the staff A, and which is cast with a stud, *h*, around which the dropping-wheel H is free to turn. I prefer to cover the upper end of this stud *h*, and for this purpose I cast a flat offset, 85 *g*, on one side of the gateway *g*. The wheel H is provided with ratchet-teeth *i* on its periphery corresponding in number and arrangement to the circular downwardly-flaring holes or cells *j* through the wheel. With these teeth 90 *i* engage a hooked actuating spring-pawl, *k*, and a retaining-pawl, *l*. The spring-pawl *k* is pivoted to the lower bent arm of lever E, so that at each upward stroke of the finger-lever F the dropping-wheel will be moved about its 95 axis a distance equal to the length of a tooth, *i*. The pawl *l* is fixed to one edge of the staff A, and prevents wheel H from being moved backward. It will be seen that the wheel H is given intermittent movements in one direction, and at each movement a cell, *j*, is carried 100 beneath the flexible cut-off to discharge its

contents through an opening, m , made through the bracket J , upon a cut-off or valve, L . This valve L is pivoted to a lug, n , at one end and to a connecting-rod, n' , at the other end, which rod or link is loosely attached to the lower end of the lever E . The cut-off or valve L is thus moved beneath the hole m just before a charge of corn is dropped from the wheel H , and when the finger-lever F is released the pawl k and cut-off L will be caused to spring back by the closing of the point-plate D , thus allowing the charge of corn to fall through the passage N to the bottom thereof, ready to be dropped into the soil when spring-plate D is again opened. Instead of using a vibrating cut-off, L , a simple sliding cut-off may be substituted, which would pass through a slot in the staff A and be suitably attached to an arm formed on the lever E on one side of the arm to which the pawl k is pivoted.

It will be seen that when the finger-lever is raised a charge of corn will be dropped from the lower end of the staff, and another charge will be dropped from the wheel H upon the cut-off L . When the finger-lever is released the spring point-plate D will return the parts to their former positions, close the passage N at the lower end of the staff, and drop a charge of corn from the cut-off L to the bottom of said passage.

It will be seen by reference to Figs. 3 and 4 that I bevel or score the back edges of the cells j at p . This is done for the purpose of allowing a grain to slip back when a cell is overcharged, and thus prevent clogging.

35

Having described my invention, I claim—

1. The frame G , consisting of the gateway and the offset g^2 , in combination with the dropping-wheel, the perforated bracket, the passage leading therefrom to the bottom of the staff, the cut-off valve L , and means for actuating the dropping-wheel, substantially as described.

2. The combination of the frame G , the gateway g , formed thereon, the dropping-wheel turning about a pivot on the bracket J , the pawls k l , the cut-off valve L , and the lever E , connected to the spring point-plate D and to the finger-lever, substantially as described.

3. The frame G , cast entire and consisting of the gateway g , the offset g^2 , the lugs e , and lugs f , substantially in the manner and for the purposes described.

In testimony that I claim the foregoing as my own I affix my signature in presence of two witnesses.

THEODORE HORTON.
